UNITED STATES PATENT OFFICE.

EDWARD J. BEACH, OF BROOKLYN, NEW YORK, ASSIGNOR TO BEACH, RUSS CO., OF BROOKLYN, NEW YORK, A CORPORATION OF NEW YORK.

OIL SEPARATOR.

1,405,259.

Specification of Letters Patent. Patented Jan. 31, 1922.

Application filed May 11, 1920. Serial No. 380,447.

To all whom it may concern:

Be it known that I, EDWARD J. BEACH, a citizen of the United States, and a resident of New York city, borough of Brooklyn, in the county of Kings and State of New York, have invented a new and Improved Oil Separator, of which the following is a full, clear, and exact description.

This invention relates to oil and air separators and has for an object to provide an improved construction especially adapted for use in connection with compressors, the arrangement being such that the sealing oil in the compressor is relieved from its air without interrupting the compressing or without necessitating the use of a large amount of oil.

Another object of the invention is to provide a separator for separating oil and air, wherein a plurality of baffling and expansion chambers are arranged to successively cause a deposit or precipitation of the oil while the air moves to a discharge point.

A still further object of the invention, more specifically, is the provision, in an oil and air separator, of a baffle and a straining member arranged in such a manner as to permit the passage of air without appreciable back pressure while causing a thorough separation of the air and oil.

In the accompanying drawing:

Figure 1 is a side view of a compressor with an oil and air separator shown in connection therewith, the same being in section for better illustrating the construction thereof.

Figure 2 is a fragmentary sectional view through part of a slightly modified form of separator to that shown in Figure 1.

Referring to the accompanying drawings by numeral, 1 indicates an air compressor of any desired kind which receives air through the inlet member 2 and discharges the same through the pipe 3 into the separator 4. Oil is led from pipe 5 or from any other source to the air opening 2 so as to provide a sealing liquid in the compressor 1 at all times. Air discharge pipes 6 and 7 are connected with the separator 4, said pipes having controlling valves of any desired kind so that air may be taken from either pipe or both pipes. Separator 4 is provided with a casing 8, divided into chambers 9 and 10 by division plate 11. This plate may be held in place in any suitable manner and is pro-

vided with a number of apertures 12 tapering or flaring from the lower side of the plate to the upper side. This plate is also provided with a flange 13, to which a foraminous member 14 is secured by bolts or in any other suitable manner. This member 14 is also bolted or otherwise secured to a dependent flange 15 used integral with the cap member 16 of casing 8. A deflector 17 is also connected with the plate 11 by a bolt 18 or in some other desirable manner, said deflector having a plurality of webs 19, whereby grooves 20 are provided. The auxiliary pipe 3' extends upwardly into the cone-shaped deflector 17 so that the air and oil may be discharged near the apex thereof. This will cause the oil to physically engage the deflector 17, to which it will adhere and move down by gravity until it drops off the lower edge thereof. The air will, however, not adhere to the deflector but will freely pass downwardly into the lower part of chamber 9, and from thence around the lower edge of the deflector 17 to the plate 11. Most of the oil is removed from the air by the deflector 17 but as the air passes through the apertures 12, most, if not all, of the remaining oil is removed, especially when operating at comparatively low pressure. When this is the case, air is usually drawn off or permitted to pass out through pipe 7. When operating at a higher pressure, the air is preferably caused to pass through the foraminous member 14 and out pipe 6. This member is arranged vertically, whereby the air must change direction in order to pass therein. This changing of direction is difficult for the oil and, consequently, the oil, will be deposited on the exterior surface by member 14 and will run down through the apertures 12 into chamber 9, where it is collected and discharged through the pipe 5. In this way, ample oil may be provided for sealing the blades of the compressor 1 and at the same time, the air free of oil discharged out through the pipe 6 or 7. Under some circumstances, additional cleaning action may be desirable. When such is the case, a supply of fibrous matter 21 is arranged on the upper surface of the plate 11, as shown in Figure 2. This fibrous matter may be asbestos, cotton or other material.

What I claim is:

1. An oil and air separator of the character described comprising a casing, a forami-

nous plate dividing the casing centrally into an inlet compartment and an outlet compartment, a drain pipe connected to the bottom part of the inlet compartment, an inlet pipe 5 extending through the center of the bottom of said inlet compartment and through the inlet compartment to near said foraminous plate, an outlet pipe connected to said casing at the end opposite to said inlet pipe, an 10 auxiliary outlet pipe connected with said casing adjacent said foraminous plate and opening into said outlet compartment, means carried by said foraminous plate for deflecting the matter entering said inlet chamber 15 and means arranged in the outlet chamber for causing the air to change direction before it passes into said outlet pipe.

2. An oil separator of the character described comprising a casing, a foraminous plate dividing the casing into inlet and outlet compartments, a tube extending vertically into the inlet compartment and to near the foraminous plate, an inverted cone-

shaped member secured to said foraminous plate and overlapping said tube, a tubular 25 member arranged in said outlet compartment, said tubular member being foraminous, and means for directing air from the interior of said tubular member.

3. An oil separator of the character described comprising a casing, a foraminous plate dividing said casing into inlet and outlet chambers, a tube projecting into said inlet chamber to a point near said dividing plate, an inverted cone secured to said plate 35 above said tube and overlapping the latter, a foraminous drum arranged within said outlet chamber so that the perforations of the drum rest at right angles to the perforations of the dividing plate, means directing 40 the air out of said drum, means directing the air out of said outlet chamber without passing through said drum, and an oil drain associated with the intake chamber.

EDWARD J. BEACH.
